DESIGN FOR A SHOE

James C. Pape, New York, N. Y.

Application May 12, 1934, Serial No. 51,766

Term of patent 3½ years

To all whom it may concern:

Be it known that I, JAMES C. PAPE, a citizen of the United States and resident of New York city, in the county of New York and State of New York have invented a new, original, and ornamental Design for a Shoe, of which the following is a specification, reference being had to the accompanying drawing, forming part thereof, in which,

Fig. 1 is a side elevation of a shoe showing my new design; and

Fig. 2 is an elevation of the opposite side of the shoe shown in Fig. 1.

I claim:

The ornamental design for a shoe as shown.

Dated, May 3rd, 1934.

JAMES C. PAPE.
